FLUORESCENT LIGHT HOLDER FOR PIANOS

Hans Nicolaysen, Brooklyn, N. Y.

Application June 5, 1946, Serial No. 674,434

4 Claims. (Cl. 248—346)

1

This invention relates to fluorescent light holders for pianos.

An object of the invention is to produce a light holder which will rest firmly and securely on a piano without being bolted, screwed or otherwise marring the piano surface.

Another object is to form a bracket for suspending a fluorescent or other light and its encasing framework in such a manner that the light is positioned away from and in front of the piano.

A further object is to form an easily removable, decorative and simple bracket which can be inexpensively manufactured.

These and other objects are accomplished by forming the bracket with a base weighted at its rear and provided at its front end with an upward, forwardly, extending member projecting beyond the base. If desired, the base at its lower forward edge can be provided with a toe or downwardly extending stop to aid in retaining the bracket in position. The light frame is suspended by arms which extend upwardly and over the projecting member.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side elevation of a bracket embodying the invention and shown positioned on a piano and carrying a light.

Fig. 2 is an enlarged perspective view of the bracket shown in Fig. 1.

Fig. 3 is a plan view of the bracket shown in Figs. 1 and 2.

Fig. 4 is a front elevation of the same bracket.

Fig. 5 is a side elevation of the bracket.

Fig. 6 is a vertical sectional view.

Fig. 7 is a sectional perspective view showing a variation of the invention.

Fig. 8 is a perspective similar to the view shown in Fig. 1 but of another variation of the invention.

In the drawings and in the specification, in which like numbers indicate similar elements, a bracket 10 shown in Figs. 1-6 inclusive, is comprised of a base 11, toe board 12, a projecting element 13, and a weight 14. In Fig. 1, the bracket is shown positioned on the top of an upright piano and suspending a fluorescent light frame (shown in phantom).

The base 11 is formed with a flat underface 15, an upper face 16, a rear end 17, front end 18,

and sides 19. The upper face 16 is provided with a longitudinally extending recess 20 running from side to side and positioned in the vicinity of the rear end 17. The recess is preferably hemispherical in cross section, although it could be of any other shape. The sides 19 are formed with portions 22 and 23 which are normal, respectively, to the rear and front ends and with an angled portion 24 which slopes outwardly from the portion 10 22 to the portion 23 widening the forward part of the base.

The toe board or stop 12 is positioned against the front end 18 of the base. The toe is shorter but wider than the front 18. The board 12 is longitudinally centrally positioned on the front end 18 and flush with the upper face and extends below the upper face and forms a toe or shoulder 25. The board is held securely against the front face by the screws 26. However, other holding means such as glue or dowels may be used, if desired.

The projecting element 13 is formed with front and rear faces 27 and 28, side faces 29, an under face 30 directioned to form an acute angle with 15 the rear face and a bevelled or convex rounded face 31 extending between and joining the rear and front faces. The element is positioned on the base in the vicinity of its front end with the under face of the element and the upper face of 20 the base glued together as at 32 (see Fig. 6). The side faces 29 of the element flush with the portions 23 of the sides 19 of the base, and with the front face 27 extending upwardly and forwardly so that a portion of the convex face 31 adjacent the face 30 25 overhangs the front ends 18 of the base and the toe board 12.

The weight 14 is cylindrical in form and rests in the recess 20, with its ends 33 adjacent the side portions 22 of the base. The weight 14 (see Fig. 40 6) is formed of a tubing 33^a filled with a heavy material 34 such as sand, shot or the like. A cork 35 (see Fig. 3) forms a closure at either end of the tube. A screw 36 (see Fig. 5) extends through the underface of the base and into the tubing and holds it securely in position.

The weight holds the base firmly on the top of the piano while the projecting element holds or suspends the light in front of and out of contact with the front of the piano, and the toe board resting against the front edge of the piano top prevents the bracket from being slid to such a position on the piano top that the light hanging over the convex face 31 comes into contact with the front of the piano.

55 A modified bracket 37, shown in Fig. 7, is com-

prised of a base 38, weight 39, projecting element 40 and a toe board 41. The base 38 is formed with its upper face 41' having a longitudinally extending projection or raised portion 42, hemispherical in cross section and positioned toward the rear of the base. A longitudinally positioned hole or socket 43 is concentric with the projection and extends completely across the bracket. The hole carries the weight 39, removing the necessity for screwing or otherwise securing in position. In all other respects, the bracket 37 is similar to the bracket 10.

A further modified bracket 44, shown in Fig. 8, is comprised of a base 45 having a front face 46, end sides 47, weight 48, a forwardly inclined projecting element 49 and with two hooks having downwardly extending shanks 51, which are secured into the front face of the base, one in the vicinity of each of the sides. The shanks 51 of the hooks projecting from the face 46 extend below the base to form a catch or stop to engage the piano top. In all other respects, the bracket 44 is similar to the bracket 10.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A bracket suitable for resting on a piano and suspending a light containing frame having hooks, comprising a base, a projecting element and a stop means, the base having a sufficient and properly positioned weight to retain the bracket in position on a piano top against the rotating force of the suspended light frame, the projecting element positioned on the base and extending upwardly and forwardly therefrom and overhanging the forward edge of the base, the stop means being positioned at the lower forward edge of the base extending below the base whereby the base is held from sliding backward.

2. A bracket suitable for resting on a piano and sustaining a light containing frame, comprising a base, a weight, a projecting element and a stop means, the base having a recess adjacent one of its edges, carrying the weight, the projecting element extending upwardly and forwardly from the base and overhanging the stop means, the stop means positioned on the side of the base removed from the recess and part of the stop means extending below the base, whereby the weight holds the base firmly against the piano and the stop means prevents the base from being slid backward.

3. A bracket suitable for resting on a piano top and sustaining a light containing frame having hooks, comprising a base, a weight, a stop means and a projecting element, the base having a longitudinally extending hole through its rear, the weight resting in the hole, the stop means positioned at the front of the base and extending therewith, the projecting element extending upwardly and forwardly from the base and overhanging the stop means.

4. A holder for supporting a fluorescent lamp from the top of a piano and in front of a piano, comprising a base having a socket formed therein, a weight disposed in said socket, an upwardly and forwardly inclined member on said base extending forwardly thereof to receive a hanger for a fluorescent lamp, and a stop secured to the forward side of the base and projecting below the base to engage the top of a piano, whereby the projecting member will be located forwardly of the front of the piano when the base is positioned on the top of a piano.
